W. FRAKES

DIAL FOR CLOCKS

Filed June 24, 1922

Inventor
William Frakes

UNITED STATES PATENT OFFICE.

WILLIAM FRAKES, OF GRAND FORKS, BRITISH COLUMBIA, CANADA.

DIAL FOR CLOCKS.

Application filed June 24, 1922. Serial No. 570,753.

To all whom it may concern:

Be it known that I, WILLIAM FRAKES, a subject of Great Britain and Ireland, residing at Grand Forks, in the Province of 5 British Columbia, in the Dominion of Canada, have invented a new and useful Dial for Clocks, of which the following is a specification.

My invention relates to an improved 10 hour dial for the clock, or time piece, whereby the correct local mean time may be kept by the clock, on the meridian it is situated upon. Also it indicates the corresponding Greenwich, mean time, or Washington 15 mean time as circumstances may require.

The dial will also denote those points on the earth's surface where it is noon or midnight.

It will be seen later in this specification, 20 such a dial will obviate the necessity for time zones on the North American or other continents and establish a natural standard time as kept by the sun throughout the world. Moreover the clock divides the sun's 25 diurnal arc into two equal parts, thus giving the same amount of daylight, both a. m. and p. m. (error in equation of time excepted).

The dial is constructed in two parts, first, 30 the central part, A, B, for local time also a. m. and p. m., and the two hands. The circle A enumerates the hours from noon to midnight on the right hand semicircle, and from midnight to noon on the left hand semicircle. In the circle B, the minutes of 35 time are recorded as on the ordinary dial, the minute hand crossing the semidiameter of the dial in the usual manner. The hour hand differs from the ordinary hour hand, by stretching clear across the two parts of the dial, as shown in the drawing. The positive point of this hand, marked "Noon at" moves in unison and harmony with the sun, thus indicating the 40 meridian with which it is in transit. The opposite, or negative point of this hand marked "Midnight at" naturally indicates the longitude where it is midnight.

The second or outer part of the dial, comprising the circles C D E F is movable and can be slid around to meet the required adjustment for longitude. In the drawing at circle F two small lugs are attached for this purpose. On the real dial these may be superseded by small metal attachments, and

the dials themselves will be of some suitable metal also.

Circle C enumerates the hours of Greenwich mean time both a. m. and p. m.

Circles D and E combine longitude and 60 time. In circle D longitude is enumerated every 15° equalling one hour of time, and each 15° is again subdivided into three parts of 5° , each equal to twenty minutes of time. Circle E again subdivides each 5° into one 65 degree sections equalling 4 minutes of time. Circle F gives geographical names of well known cities and countries of the world, and these are placed opposite their respective longitudes.

Special note may here be made in reference to circles D and E. Time read from these circles would be the same in any part of the world, as the sun, and the positive point of the hour hand, are moving in 75 unison on this circle. Therefore an observer, at a glance can read off the corresponding local time at his meridian: This is done by observing the time indicated on dial A by the positive point of the hour hand, the movable part of the dial having first been adjusted so that the "12 o'clock, noon" indication on dial D is opposite the longitude of the place whose local time is 80 required. The difficulties caused on rail- 85 ways by the time zones could be removed or greatly reduced by running all trains according to the "civil time" (that is Greenwich time, or the time at any other agreed place) and using clocks provided with dials 90 according to my invention for reducing "civil time" to the local time, at every station. Time tables for local use could be compiled by using a clock dial according to 95 my invention for reducing the times given on the general time tables (which would give "civil time") to the corresponding local times. Railway time tables, &c., could be compiled from these circles, and transferred to the equivalent local time, so that time 100 zones would not be necessary.

The clock being set in its place, and the longitude obtained, adjust the clock to this longitude by sliding the outer part of the dial, (circles C D E F) so that the corresponding longitude on this circle cuts under the hairline G at the noon of the local dial, and clamp the adjustable part of the dial permanently. The hairline G is secured 105 at one end to the edge of the dial A B at 110

G¹ and at its other end to the clock casing Z as indicated in the drawing. The clock casing also supports one or more fixed brackets Y carrying set-screws M adapted to engage 5 against the surface of the movable part of the dial, to hold it in adjusted position. Clamps are not shown in the drawing. For example, say the clock is set up in Washington, D. C. The longitude being 77° west of Greenwich. 10 Bring 77° of west longitude under the hair line as above, and suppose it noon at Washington, D. C., local mean time, you will note the Greenwich mean time to be 5hr. 8m. p. m. and the time at Singapore to be 15 midnight.

Again say your local time reads 3hrs. 36m. p. m. Corresponding Greenwich mean time reads 8h. 44m. p. m. and on a meridian about 20 Port Simpson, B. C., it is noon and on a meridian passing through the Island of Madagascar it is midnight. It will be noted in circles D and E the Greenwich mean time can be read to 4 minute intervals only, but the minutes of Greenwich mean time may 25 also be read from the minute hand of the clock. Example, say minute hand reads 22 minutes, add to this the number of minutes of the adjustment. Say adjustment 5h. 8m. Greenwich mean time add 8m. to 22m.=30m. 30 Greenwich time.

In east longitude the difference of minutes is subtractive.

I claim a clock dial as set forth in the above specifications and drawings as my invention and what I desire to secure by Letters Patent is:—

1. A geographical clock comprising a fixed inner twenty-four hour dial and an outer dial concentric therewith and adjustable thereabout at will, said outer dial being divided into twenty-four hour divisions and three hundred and sixty degrees of longitude.

2. A geographical clock according to 45 claim 1 including names of places in and

parts of the world marked on said outer dial opposite the corresponding degrees of longitude.

3. A geographical clock comprising a fixed inner twenty-four hour dial, an outer dial adjustable thereabout at will, degrees of longitude marked on said outer dial, names of places in and parts of the world marked on said outer dial opposite the corresponding degrees of longitude and an hour hand stretching clear across said dial and having diametrically opposite positive and negative points. 50

4. A geographical clock according to claim 1 including an hour hand stretching clear across said dial and having diametrically opposite positive and negative points. 60

5. A geographical clock according to claim 1 including an hour hand stretching clear across said dial and having diametrically opposite positive and negative points, names and places in and parts of the world being marked on said outer dial opposite the corresponding degrees of longitude. 65

6. A geographical clock according to claim 1 including lugs on said outer dial for adjusting same.

7. A geographical clock comprising a fixed inner twenty-four hour dial, an outer dial concentric therewith and adjustable thereabout at will, twenty-four hour divisions and three hundred and sixty degrees of longitude marked on said outer dial, names of parts of and places in the world marked on said outer dial opposite the corresponding degrees of longitude, and an hour hand stretching clear across said dial and having diametrically opposite positive and negative points. 75 80 85

WILLIAM FRAKES.
